UNITED STATES PATENT OFFICE.

JAMES F. McLAUGHLIN, OF ERIE, PENNSYLVANIA.

MOP.

936,655.

Specification of Letters Patent.

Patented Oct. 12, 1909.

Application filed April 25, 1908. Serial No. 429,119.

To all whom it may concern:

Be it known that I, JAMES F. McLAUGHLIN, a citizen of the United States, residing at Erie, in the county of Erie and State of Pennsylvania, have invented new and useful Improvements in Mops, of which the following is a specification.

This invention relates to mops and consists in certain improvements in the construction thereof as will be hereinafter fully described and pointed out in the claims.

The object of the invention is to provide a mop which will carry a mop cloth, and also a mop brush either together or separately.

The invention is illustrated in the accompanying drawings as follows:

Figure 1 shows the mop head partially opened. Fig. 2 is a side elevation of the head closed with a brush in place. Fig. 3 a front elevation, with the parts similarly arranged.

1 marks the mop stick. The end 1^a of the stick is cut down slightly from the size of the remaining stick. A thimble 2 is secured 25 to the end of the stick and has the double lips 3 at each side forming the groove or guide way 4 between them. The head 5 is carried by the sliding supports 6. These sliding supports 6 extend through the way 4. The sliding supports terminate in a ring 7 which encircles the stick, the ring being 30 of sufficient size to operate over a coiled spring 8.

A lever 10 is secured to the projections 9 on the end of the spring 8 at each side, the spring forming a fulcrum or base for the lever. The bail 11 is pivotally secured to the lever and extends through the grooves 12 on the head, and is arranged in proper 40 relation to the head to engage a cloth to clamp it on the head.

A brush finger 13 is fixed on the thimble 2, and has a lug 14 for engaging the end of the brush. Lugs 15 extend from the head 45 5 in position to engage the opposite side of the brush. A brush 16 is shown in place in Figs. 2 and 3.

The bail has a turn 17 which will engage the head before the lever 10 is thrown the 50 limit of its movement in the opening direction, thus the head 5 is moved sufficiently to open the jaws for the brush by the action of the lever.

When it is desired to place a cloth in the 55 mop it is put into position between the bail and the head, the lever being thrown for-

ward or toward the end of the stick. As the lever is drawn back the spring 8 yields sufficiently to allow for the insertion of the cloth. At the completion of the movement 60 of the lever the centers are brought to such a position to lock the lever in its closed position against the stick. The cloth is then clamped between the bail and the head by the force of the spring. The end of the 65 thimble forms a stop which limits the rearward movement of the head with relation to the stick, so that the spring is compressed slightly when the bail is brought into position on the head regardless of whether there 70 is a brush in the clamp or not.

When the head is pushed forward by the action of the turn 17 and lever, a brush 16 may be readily inserted between the brush finger and the head. As the lever is drawn 75 back in the manner of clamping the cloth the bail is drawn against the head, and the head against the brush, so as to firmly clamp the brush in place, the brush forming in this instance the stop for the head. The 80 throw of the lever is long enough and the play of the coiled spring sufficient to permit the insertion of both the cloth and the brush. On the other hand the spring will be put under compression with an insertion of cloth 85 alone, the head being against the stop or thimble 2.

What I claim as new is:

1. In a mop, the combination of a stick; a head slidably mounted on the stick; a 90 brush finger fixedly mounted on the stick; a stop for limiting the movement of the head on the stick; a bail operating on the head to clamp a mop; and a yielding pressure device for the bail adapted to actuate the bail to 95 yieldingly engage the head.

2. In a mop, the combination of a mop stick; a support having a sliding engagement with the stick, said sliding support terminating in a ring surrounding the stick; a 100 head secured to the support; a bail for clamping a mop on the head; a brush finger fixedly mounted on the stick opposite the head; a spring mounted on the stick; and means for conveying the pressure of the spring to 105 the bail.

3. In a mop, the combination of a mop stick; a thimble at the end of the stick having guiding lips thereon; a head having supports slidably mounted between said lips; 110 a bail for clamping a mop on the head; a brush finger fixedly mounted on said thimble

opposite the head; and a yielding pressure device for the bail adapted to actuate the bail.

4. In a mop, the combination of a mop stick; a thimble on the end of the stick having guiding lips thereon; a head having supports slidingly mounted between said guiding lips; a ring secured to the supports and encircling the stick; a bail acting on the head; a brush finger fixedly mounted on the thimble opposite the head to clamp a mop thereto; a coiled spring surrounding the head extending within the ring against the thimble; and means for conveying the pressure of the spring to the bail.
5. In a mop, the combination of a mop

stick; a head slidingly mounted on the stick; a bail acting on the head to clamp a mop thereto; a brush finger fixedly mounted on the stick opposite the head; and a lever for 20 operating the bail, said bail having a sliding engagement with the head, and being bent inwardly to engage the head as the lever is thrown in an opening direction to move the head away from the brush finger.

In testimony whereof I have hereunto set my hand in the presence of two subscribing witnesses.

JAMES F. McLAUGHLIN.
